ADOLF MEYER, OF KUSNACHT, NEAR ZURICH, AND KARL FREY, OF ENNETBADEN, SWITZERLAND, ASSIGNEES TO A. G. BROWN BOVERI & CIE., OF BADEN, SWITZERLAND, A JOINT-STOCK COMPANY OF SWITZERLAND.

STEAM-TURBINE CONSTRUCTION.

Application filed February 19, 1926, Serial No. 89,451, and in Germany April 23, 1925

This invention has to do with steam turbine construction, particularly with the arrangement of the cylinder or diaphragm blade mountings for disposal of water condensed in 5 the turbine.

The general object of the invention is the provision of a construction whereby water of condensation may be discharged or withdrawn from the cylinder blading, and which 10 may be built economically and without weakening the cylinder or adding to its weight or bulk.

Other objects will be pointed out or indicated hereinafter, or obvious to one skilled 15 in the art upon an understanding of the present disclosure.

In the accompanying drawing forming part of this specification are shown, in a dia- 20 grammatic fashion, various embodiments of the invention, but it is to be understood that these are presented for the purpose of illustration only and are not to be construed in any fashion such as to limit the invention claimed short of its true and comprehensive 25 scope in the art.

Fig. 1 is a sectional diagram illustrating the passage of steam and water from a stage 30 of guide blades to a stage of rotor blades in a steam turbine.

Fig. 2 is a detail in the nature of a part longitudinal section through a portion of an impulse turbine showing the arrangement at the junction of the diaphragm or the blade mounting and casing or cylinder.

Fig. 3 is a similar section through the mountings of adjacent guide blade stages, showing a modification.

Fig. 4 is a cross sectional view through the mounting of a guide blade.

Fig. 5 is an elevational sectional detail through adjacent guide blade mountings, showing another modification.

Fig. 6 is a similar view of a modification of the form shown in Fig. 5.

Fig. 7 is a longitudinal sectional detail on approximately line 7—7 of Fig. 5.

Fig. 8 is a transverse sectional elevational detail through the lower portion of the cylinder, and

Fig. 9 is a longitudinal section elevational view showing the arrangement of discharge channels.

Considerations of efficient operation of steam turbines make desirable the use of the

highest feasible steam pressures and vacua 55 for the purpose of giving the greatest possible heat drop. Increase in pressure and vacuum is attended, however, with the undesirable effect of increasing condensation of steam in the low pressure stages of the turbine, resulting in loss of energy and erosion of the blading.

It has been proposed to provide annular channels cast in the cylinder between the stages of guide blades for the purpose of 60 conducting off the condensate. Such constructions, however, considerably increase the cost of the casing and when formed by cutting, weaken the same unless the casting is reinforced by additional thickness. This, 65 however, means further increased cost attended with the danger of there being pipes in the casting owing to the extensive thickness of metal. By the present invention we 70 obviate these difficulties and provide an effective construction which makes adequate provision for the disposal of the condensate, lends itself readily to manufacturing operations, involves no additional parts, is easily 75 assembled, and occasions no weakening or increase in bulk of the casing or of the blading or blade mounting. This we accomplish by forming the blade mounting of the casing or cylinder in such a fashion as to provide annular spaces for conducting off the condensate 80 between the stages of blade mountings, with suitable communicating passages extending through the blade mountings for permitting flow of the condensate longitudinally 85 of the casing to discharge channels.

The nature of the invention will be understood more in detail from the illustrative forms shown. In the first place, to demonstrate the detrimental effect of accumulations of condensate in the blading, reference is 90 made to Fig. 1, where *a* designates a stage of guide blades and *f* an adjacent stage of rotor blades. The component *c* designates velocity of steam leaving the guide blading, and *b* the velocity of water leaving the same. Subtracting the peripheral velocity *u* gives resultant *e* with which the steam enters the moving blades in the most favorable direction. The water, however, leaves in the direction *d* striking the backs of the moving blades at *g*, resulting in a force opposing their movement and in destructive erosion.

In Fig. 2 is shown a construction for a

cylinder in which diaphragms are used between the rotor stages, such, for example, as in a turbine of the impulse type. In this figure the reference numeral 10 designates a portion of the casing or cylinder in which is mounted the portion 11 of the blade mounting, which, with the disc portion 12, supports the blades 14. It will be observed that portions 11 of the blade mounting are arranged 10 to extend inwardly from the bore surface of the cylinder 10, leaving an intervening annular channel 15, the lateral walls of which are provided by the blade mounting portions 11. Through these blade mounting portions 15 at appropriate intervals are formed the passages 16, providing the communicating passages between adjacent channels longitudinally of the casing, whereby the water may be drained from the channels entirely outside 20 the periphery of the guide and rotor blades. These passages are provided at such intervals as may be appropriate and in most instances will be arranged at closer intervals in the bottom portion of the cylinder than in the more 25 elevated portions. In Fig. 3 is shown another construction wherein the blade mountings are in the nature of extension or root portions formed on the blade, together with separate spacing members inserted between the 30 blade roots and operating to anchor them in place in annular slots in the casing, the casing here being designated 10', the blades 14' and the blade mountings 11'. In this form, as in the form illustrated in Fig. 2, the passages 16 are shaped as tunnels or bores. Fig. 4 shows the cross sectional view, illustrating one shape of the spacing members 11^a which form part of the blade mounting. In Figs. 7 and 5 is shown another form of the blade 35 mounting, in which the passages 16 are formed as grooves extending transversely in the spacing pieces with their bottoms flush with the bore surface of the cylinder. In Fig. 6 is shown yet another arrangement 40 in which the spacing members 11^a of the blade mounting are reduced in height throughout their full area so as to be flush with the bore of the cylinder. It will be understood that with any of these various 45 embodiments the spacing members are formed to afford the passages which are ar-

ranged at appropriate intervals in the stage of guide blading. In Fig. 8 a number of them are shown interposed between adjacent blades at the lower portion of the casing. For the purpose of removing the condensate from the casing, the latter may be provided with longitudinal conduits 17 communicating with channels 15 by way of the passages 18, the casing being increased in thickness as at 19, 60 if desired, to accommodate said conduits. This may be done without increasing the weight of the casing. Of course, various other arrangements of discharge passages may be provided. 65

What we claim is:

1. In steam turbine construction, a stator casing, and fixed blade mountings extending inwardly from the casing bore surface to afford intervening channels extending in the circumferential direction of the casing, said mountings being provided with passages arranged for drainage of liquid from one of said channels to another. 70
2. The construction as in claim 1, wherein the outer walls of the passages are flush with the casing bore surface. 75
3. The construction as in claim 1, wherein the blade mountings include spacing pieces between blades, said passages being provided 80 through the spacing pieces.
4. The construction as in claim 1, wherein the blade mountings include spacing pieces between blades and the passages extend the full width of the spacing pieces. 85
5. The construction as in claim 1, wherein the casing wall affords longitudinal conduits for conducting condensate away from the channels. 90
6. The construction as in claim 1, wherein the blade mountings are of annular form. 90
7. The construction as in claim 1, wherein the outer walls of the channels are the normal bore surface of the casing. 95
8. The construction as specified in claim 1, wherein outlets are provided for conducting condensate away from said channels.

In testimony whereof we have hereunto subscribed our names at Zurich, Switzerland, on the 20 day of January, A. D. 1926.
